BUFFING AND ABRASIVE DEVICE

Filed July 7, 1930

UNITED STATES PATENT OFFICE

BENJAMIN A. CASPER, OF MINNEAPOLIS, MINNESOTA

BUFFING AND ABRASIVE DEVICE

Application filed July 7, 1930. Serial No. 465,910.

This invention relates to polishing and abrasive devices such as are used for cleaning and buffing floors and walls of buildings, and while adaptable for a wide general use in abrasively treating and cleaning metal, wood, and other material, it is especially well suited for cleaning and re-conditioning floors and woodwork.

The buffer or abrasive element of my device utilizes steel wool as the cleaning and abrasive medium, and the steel wool is so applied and mounted on the spool or other holding member or element that it will penetrate into the crevices and interstices of the wood or other material, thoroughly cleaning and buffing the same longitudinally of the grain of the material.

Steel wool in matted or blanket form has of course been extensively used for polishing and scouring, and some effort has been made to successfully use matted steel wool in a rotary buffer. Prior devices known to me, however, have been impractical for the reason that the steel wool will become detached from the rotary holding element, and further, the filaments of the steel wool being matted and crossed, will scratch transversely of the grain and will not penetrate the interstices of the wood to clean the same.

It is an object of my invention to provide a comparatively simple but highly efficient buffer and abrasive device utilizing steel wool, wherein the wood is treated longitudinally of the grain by a multiplicity of steel filaments extending circumferentially of the buffing element, and wherein the steel wool is wound spirally about the spool forming successive layers of filaments, thereby preventing detachment of the steel wool from the buffing element.

It is a further object to provide a buffer and abrasive device of the type described, and a frame or mounting for the same, wherein by the filaments of the steel wool will be applied tangentially to the surface treated.

These and other objects will be apparent from the following description made in connection with the accompanying drawing wherein like reference characters refer to

similar parts throughout the several views, and wherein:

Figure 1 is a side elevation of a floor treating machine embodying my invention.

Figure 2 is a cross section taken on the line 2-2 of Figure 1.

Figure 3 is a cross section taken on the line 3-3 of Figure 2, and showing the winding of the steel wool filaments upon the spool.

Figure 4 is a perspective view showing the manner in which the strands or filaments of steel wool are wound upon the spool, and

Figure 5 is a side elevation of a buffing or abrasive element which may be attached to one end of the buffing shaft.

As illustrated in the drawing my rotary buffing or abrasive element comprises an elongated hollow spool 6, having the flanged circular ends 7, which are provided with centrally disposed keyhole-shaped apertures 7^a, the circular portion of aperture 7^a being disposed concentric with spool 6. The circular ends 7 are rigidly fixed to ends of spool 6 or may be integrally constructed therewith. The spool proper is preferably constructed of wood or some fibrous or roughened material.

Steel wool is obtained and combed or prepared in such manner that the individual filaments extend substantially parallel in the form of a ribbon, and the ribbon, comprising a series of these filaments, is carefully wound upon spool 6 as illustrated in Figure 4, forming spiral layers of the metal filaments. In beginning to wind the steel wool the end of the ribbon may be affixed to the spool or may be lapped under the next winding and tightly drawn against the spool, the intent being to secure the windings so that there will be no slippage or displacement of the steel wool from the spool. The buffer element formed by the spiral windings is considerably larger in diameter than the ends 7 of the spool in order that the surface may be efficiently treated by the cylindrical surface of the buffing element rather than the ends thereof.

It will of course be understood that various machines or other means for supporting and driving my rotary buffing element may be

utilized, all within the scope of the invention.

In the form of the machine disclosed for floor treating, a suitable frame F is supported at its rear ends and intermediate portions by four rollers 8. The frame may comprise spaced side bars secured together by cross-beams, or may comprise an integral plate having ears or apertured portions for receiving the rollers 8. At the front of the frame a segmental-shaped hood 9 is rigidly secured, wherein the rotary buffing element is partially housed. Hood 9, as shown, has spaced ends provided with vertical guides 9^a, which may be cast or otherwise formed therein, and the said guides each include two sets of spaced flanges 9^b, the flanges of each set defining a slot through which the driving shaft 10 of the buffing element may horizontally extend. Bearing blocks 11 are slidably mounted in each of the vertical guides 9^a. These bearing blocks are yieldingly pressed in a downward direction by means of coil springs 12 which are housed in the guides 9^a, and engaging at their lower ends the upper surfaces of the blocks 13. The downward movement of bearing blocks 11 within the guides 9^a is limited by means of stop screws 9^c, which may be horizontally threaded into the side portions of the vertical guides 9^a. The driving shaft 10 extends through the slotted portion of the guides, through the bearings 11, and through the hollow spool 6, and is provided adjacent its ends with small keys 10^a, which interlock with the slotted portions of the key-hole apertures 7^a in the ends of the spool. Shaft 10 is prevented from longitudinal displacement by suitable means, such as collars 15 and 16 affixed to the outer ends thereof. One end of the shaft 10 has rigidly affixed thereto a silent chain sprocket 17 which is connected by silent chain 18 with a sprocket 19 of a gear-reducing member. The gear-reducing member is mounted on a stub shaft 20 journaled horizontally and transversely in a suitable bearing provided at the medial portion of frame F. A suitable electric motor M may furnish the source of driving power and, as shown, is mounted upon the medial portion of frame F with its armature shaft extending transversely of said frame, and carrying a small driving pinion 21, which is in mesh with a large gear 22 affixed to the gear-reduction shaft 20.

An attachment bracket 23 may be fixed at the rear of the casing of motor M, and to the attachment bracket an elongated handle 24 is pivotally secured at its inner end, and may be rigidly connected in a number of different radial positions with respect to bracket 23 by means of a spring-pressed tooth 25 operated by a lever 26 and a link 26^a, said lever being conveniently disposed for operation adjacent the outer end of handle 24. The tooth 25 is adapted to engage a series of ra-

dially disposed sockets 23^a formed in attachment bracket 23.

In Figure 5 an attachment buffing member is illustrated which is especially adapted for use in cleaning floor boards or moldings which extend slightly above the level of the floor. This attachment member comprises a relatively short spool 28 upon which is spirally wound, in the manner previously described with reference to the winding of spool 6, a series of strands of steel wool or other metal filaments W. The spool 28 is rigidly attached to a shaft 28^a, which may be substituted in the machine for the driving shaft 10 of the buffer element illustrated in Figures 1 to 4.

In operation the rotary buffing or abrasive element is disposed tangentially with reference to a surface to be treated, and in floor-conditioning machines the buffer element is moved across the floor longitudinally of the grain of the wood. The metal filaments or strands extending circumferentially of the spool 6 engage the interstices of the wood, removing dirt and dust therefrom and reconditioning the same. The rotary element will never scratch cross grain of the wood since the winding of the steel wool is circumferentially of the spool, and since the rotary element is applied tangentially to the surface treated and with the filaments extending longitudinally of the grain.

It will further be seen that as the outer layers of the spiral windings become worn, the next successive layers are exposed for application to the surface, and the mass of steel wool will never be disintegrated or separated from the spool until the same is completely consumed and worn by friction against the surface treated. The buffing or abrasive element is of course driven in such a direction that the friction thereof against the surface will tend to wind the strands of metal tighter upon the spool rather than to unwind the same.

In the particular form of machine illustrated in the drawing the buffing and abrasive element may be very conveniently applied to a floor, the frame F being mounted for travel over the floor on rollers 8. When it is desired to lift the buffing element from engagement with the floor, the handle 24 may be swung downwardly, placing the weight of the motor and frame mostly upon the rear rollers of the frame. The bearings for the driving shaft 10 of the element are yieldably mounted, enabling the buffing element to properly conform to variations in the contour of the surface treated. The horizontal position of the buffing element as well as the tension upon the springs 12 may be quickly and easily varied by adjusting the winged bolts 14. The hood or guard 9, partially housing the buffing element, prevents dust, dirt, and broken particles of the steel wool from flying

back against the operator. As indicated in Figures 1 and 3 the buffing and abrasive element is preferably rotated in a direction opposite to the travel of the machine over the 5 surface.

In the foregoing description it will be seen that I have invented a simple but highly efficient buffing device adapted to be manufactured at relatively low cost, and capable 10 of wide general usage for cleaning, polishing, reconditioning, and abrasively treating surfaces. The particular winding and mounting of the buffing and abrasive element renders it especially well adapted for efficiently treating fibrous material which has 15 grain, and for penetrating the interstices of the outer surface without scratching or marring the appearance of the material. The buffing and abrasive elements may be used 20 without disintegration of masses of steel wool, since the strands are spirally and circumferentially wound upon the spool, and as the outer layer of steel filaments becomes worn, a new and fresh layer is substituted. 25 It will of course be understood that various changes may be made in the form, details, proportions, and parts without departing from the scope of my invention, which, generally stated, consists in a device capable 30 of carrying out the objects of the invention, and as defined in the appended claims.

What is claimed is:

1. A floor surfacing machine of the power driven type including a rotary spool arranged for rotation about an axis paralleling the floor and transverse to the direction of movement of the machine over said floor and abrasive material upon said spool in the 40 form of a multiplicity of metallic filaments wound helically thereof so as to present spirally disposed abrasive edges of said filaments to said floor.

2. A floor surfacing machine of the power driven type including a rotary spool arranged for rotation about an axis paralleling the floor and transverse to the direction of movement of the machine over said floor and abrasive material upon said spool in the 50 form of a multiplicity of substantially parallel filaments of steel wool wound helically thereof so that the abrading edges of said wool extend spirally of said spool.

3. A floor surfacing machine of the power driven type including a rotary spool arranged for rotation about an axis paralleling the floor and transverse to the direction of movement of the machine over said floor, an abrasive material upon said spool in the 60 form of a multiplicity of metallic filaments wound helically thereof in a series of successive layers and presenting helically disposed abrasive edges to the floor.

4. A floor surfacing machine of the power driven type including a rotary spool arranged for rotation about an axis parallel-

ing the floor and transverse to the direction of movement of the machine over said floor and abrasive material upon said spool in the form of a multiplicity of elongated metallic filaments wound helically upon said spool from one end to the other end thereof and then helically back from the second end toward the first mentioned end to form a plurality of layers presenting helically disposed abrasive edges to said floor.

In testimony whereof I affix my signature.

BENJAMIN A. CASPER.
